Merle G. Carr
ATTORNEY

UNITED STATES PATENT OFFICE.

CHARLES W. STARKER, OF PITTSBURGH, PENNSYLVANIA, ASSIGNOR TO WESTINGHOUSE ELECTRIC & MANUFACTURING COMPANY, A CORPORATION OF PENNSYLVANIA.

BLOWER FOR DYNAMO-ELECTRIC MACHINES.

Application filed February 8, 1918. Serial No. 216,106.

To all whom it may concern:

Be it known that I, CHARLES W. STARKER, a citizen of the German Empire, and a resident of Pittsburgh, in the county of Allegheny and State of Pennsylvania, have invented a new and useful Improvement in Blowers for Dynamo-Electric Machines, of which the following is a specification.

My invention relates to air-agitating devices that are adapted to be attached to rotatable members, and it has for its object to provide a device of the character designated of such nature that the amount of air caused to circulate may easily be varied to conform to existing conditions.

Heretofore, it has been customary to construct fan members of such nature that each different size of machine required fan members built for its own individual use and usually were mounted on a ring member which had to be of the same diameter as the rotating element to which it was attached. By my invention, I provide fan members, each of which is individually mounted on the rotating element and is of such design that a single member may be employed on any one of a number of machines of a considerable range of sizes.

Referring to the drawings, Fig. 1 is an isometric view of the rotor of a dynamo-electric machine provided with a fan member constructed in accordance with my invention; and Fig. 2 is a detail view of a slight modification of the fan member shown in Fig. 1.

Referring more particularly to the drawings, I have shown a shaft 1 on which a rotatable element 2 is mounted. Fan members 3 are mounted on the rotatable element 2, 40 in diametrically opposite positions, by means of bolts 4. The fan member 3, as shown in Fig. 2, consists of two substantially U-shaped members 5 and 6, each of which consists of main body portions or shrouds 7 of arcuate form, and leg portions 8 at its ends which are integral with the main body portions 7 and extend at right angles thereto. The leg portions 8 of the U-shaped members 5 are provided with flanges 9 having slots 10 therein through which the bolts 4 extend for attaching the fan members to the rotatable element 2. The U-shaped members 5 and 6

are attached to each other by any suitable method, such, for example, as by welding. 55 The slots 10 in the flanges 9 aid in rendering the fan members adjustable to various sizes of machines.

Fig. 2 shows a slight modification of my invention in which a single L-shaped member 11 is attached to the shroud 7, replacing the U-shape member 6 of Fig. 1.

It is obvious that any number of fan members may be attached to a single rotating element in order to produce the desired amount of ventilation, the number being limited only by the space on the rotating element necessary for mounting the fan members. It will also be readily apparent that a fan blade member constructed in accordance with my invention is not limited to any one size of machine but may be employed on any machine the radius of which is within reasonable range of the radius of the main body portion of the fan member 75 which is arcuate in form.

While I have shown one form of my invention, it will be obvious to those skilled in the art that it is susceptible of various minor changes and modifications without departing from the spirit thereof, and I desire, therefore, that only such limitations shall be placed thereupon as are imposed by the prior art or are specifically set forth in the appended claims.

I claim as my invention:

1. In combination with a rotor member, an air-propelling device comprising a unitary pressed member disposed in spaced and parallel relation to the face of said rotor 90 and having the extremities thereof bent to form a plurality of supporting feet and a member of substantially U-shape adapted to be secured to said pressed member and disposed between the same and the face of 95 said rotor member.

2. In combination with a rotor member, an air-propelling device comprising a single member having a central portion disposed parallel to the face of the said rotor member but spaced therefrom, said member having the end portions thereof bent parallel to, and into engagement with said face, and portions intermediate said central and said end portions bent perpendicular to said face. 100

3. In combination with a rotor member,

an air-propelling device comprising a substantially U-shaped member, the main body of which is arcuate in form and is spaced from said rotor member and disposed substantially at right angles to the axis thereof and the leg members of which are disposed parallel to said rotor member axis and are attached to said rotor member.

4. In a dynamo-electric machine, the combination with a rotor member provided with an end plate, of an air-propelling device comprising a substantially U-shaped member, the main body of which is arcuate in form and is disposed substantially at right angles to the axis of said rotor member and the legs of which are disposed parallel to said rotor member axis and are attached to said end plate by threaded fastening means.

5. In a dynamo-electric machine, the combination with a rotor member provided with an end plate, of an air-propelling device comprising a substantially U-shaped member, the main body of which is arcuate in form and is disposed substantially at right angles to the axis of said rotor mem-

ber and the legs of which are disposed parallel to said rotor member axis and are attached to said end plate by threaded fastening means and a leg member attached to said main body member and disposed intermediate the leg members of said U-shape member and parallel thereto.

6. In a dynamo-electric machine, the combination with a rotor member provided with an end plate, of an air-propelling device comprising two substantially U-shaped members, one within the other, the main body portions of which are attached together and are arcuate in form and are disposed at substantially right angles to the axis of the rotor member and having the leg portions of both of said members disposed substantially parallel to said rotor member axis and having the legs of the outermost member attached to said end plate.

In testimony whereof, I have hereunto subscribed by name this 2nd day of Feb. 1918.

CHARLES W. STARKER.
